DEVICE FOR RETAINING HEAT IN MOTOR
OIL

Septer S. Joy, Terre Haute, Ind., assignor of twelve and one-half per cent to Michael John Grogan, twenty-four per cent to Charles A. Crawford, thirty per cent to Mary Frances Craft, five per cent to George Oltean, and five per cent to Max Menistrina, all of Terre Haute, Ind.

Application September 26, 1938, Serial No. 231,844

7 Claims. (Cl. 123—196)

The present invention relates to a device for retaining heat in motor oil.

The particular problem solved by the present invention is that of providing an engine with free flowing oil at the very time it starts. The viscosity of motor oil increases with low temperatures to such an extent that the lubricating quality is impaired. A great deal of the wear of an engine, particularly an internal combustion engine, takes place in the interval between the starting of the engine and the time when the oil becomes sufficiently fluid to lubricate adequately. In cold weather oil drops in temperature in the crankcase of the engine and does not flow through the oil feeding system at the proper rate. During this time the cylinder walls, wrist pins and other parts subject to friction are not being oiled.

It is an object of the present invention to maintain a body of warm oil for drainage into the crankcase of the engine before starting so that lubrication is had at once.

A further object is to provide a device which does not interfere with the normal operation of the engine and lubricating system and which is subject to control by the operator of the engine to withdraw a quantity of oil from the crankcase and preserve the heat in the oil.

A further object is to provide a device which operates by withdrawing a quantity of oil from the crankcase and storing it to conserve its heat and at the same time providing means which prevents the starting of the engine while the quantity of oil is removed from the crankcase.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a side elevation partly in section of an automobile engine with the device of the present invention applied.

Figure 2 is a vertical section taken through the oil reservoir.

Figure 3 is a top plan view of the oil reservoir.

Figure 4 is a vertical section similar to Figure 2 with the float in uppermost position.

Figure 5 is an enlarged fragmentary view in section of the ignition cut off switch employed.

Figure 6 is a central vertical section taken through a modified form of oil reservoir; and

Figure 7 is a top plan view of the reservoir shown in Figure 6.

Referring now to the drawings, in Figure 1 an engine 10 is provided with the usual crankcase 11 and oil intake spout 12. Normally the oil for lubricating the engine is carried in the crankcase 11 and is circulated to the engine bearings by the usual oiling system. According to the present

invention a small diameter pipe 13 is placed with an end opening in the crankcase 11 near the bottom thereof. The crankcases are normally made with a low point and preferably the end of the pipe 13 opens at this low point. From the crankcase the pipe 13 extends along the outside of the dashboard 14 to the oil reservoir. As shown in Figures 2 and 4 the oil reservoir comprises a body 15 of thermos or Dewar construction. That is, the body is composed of two cylindrical members spaced slightly apart and the space between them is evacuated so as to reduce the heat conducting properties to a minimum. The top of the body 15 is closed by means of a cap 16 which is threaded over the top of the body. Inside the cap 16 an insulating disc 17 is placed. The use of such a disc permits the employment of a relatively strong metal cap. Such a disc is composed of cork, fiber, glass or any of a number of other well known heat insulating materials. If desired, the cap 16 may be formed of a heat insulating material such as one of the synthetic resins and the disc 17 may then be dispensed with.

The lower end of the body 15 of the oil reservoir is funnel shaped and connects with a return pipe 18 which, as shown in Figure 1, joins with the oil intake spout at 19. This oil return is preferably of considerably larger diameter than the pipe 13 so that oil may drain from the reservoir quite rapidly.

The motive power for withdrawing oil from the crankcase 11 through the pipe 13 is provided by the intake suction of the engine. The engine has the usual carburetor 20 surrounded according to modern design with an intake air cleaner 21. The vacuum tube 22 is connected to the carburetor at 23 which is preferably below the needle valve so that the full suction of the engine is available. The tube 22 is connected to the top 16 of the reservoir and serves to create a vacuum in the body 15 which causes oil to be lifted through the pipe 13. The cap 16 is provided with a nipple 24 which is internally threaded and receives the end of the elbow 25. The tube 22 and elbow 25 are secured to the opposite sides of a valve 26 which may be of the ordinary turning plug variety. The top 16 is also provided with a nipple 27 which is internally threaded and receives the elbow 28 which is secured to one side of the valve 29 to which the upper end of the oil pipe 13 is also secured. The turning plugs of the valves 26 and 29 have fastened thereto arms 30, 31 respectively. The arms 30 and 31 are interconnected by a control rod 32 which extends through the dashboard and the instrument panel of the automobile, as shown in Figure 1, and is provided with a control knob 33 at the driver's side of the instrument panel.

The bottom of the body 15 of the reservoir where it connects with the return pipe 18 is pro-

vided with a valve 34 which is shown in the simple form of a slidable perforated disc moving in closed guides. The valve 34 is pivotally connected to a link 35 which extends through the 5 dashboard and the link is pivotally connected in turn to an arm 36 which is pivoted to the dashboard at 37 and connects to a control lever 38. The lever 38 passes through the instrument panel 39 and is provided at the opposite side with a control knob 40.

In the operation of the device the valves 26 and 29 are both opened by pulling the control knob 33 on the instrument panel. The engine must of course be running at this time in order to create 15 the necessary suction. The outlet valve 34 will be closed by maintaining the control knob 40 against the instrument panel. Oil is then withdrawn from the crankcase 11 through the pipe 13 and delivered at the top of the reservoir. Due 20 to the insulating nature of the reservoir the oil is prevented from cooling to the temperature of the atmosphere for from twelve to thirty-six hours depending on the atmospheric temperature. When it is desired to start the car the valves 26 25 and 29 are closed and the outlet valve 34 is opened. The oil returns through the return pipe 18 into the crankcase where it mixes with the remainder of the oil and provides a fluid lubricant 30 for the motor even after the car has been standing for many hours.

With a device constructed as just described there is always a possibility that a negligent driver would start his engine and drive the car while a large quantity of oil is present in the reservoir. 35 The reservoir is designed to hold around one gallon of oil so that in a six quart crankcase there is not sufficient oil remaining to lubricate the motor adequately for any substantial period. In order to prevent this happening a switch is associated with the reservoir which keeps the motor ignition circuit open while the reservoir is filled. This switch is composed of a pair of contact plates 41, 42. The plate 41 is connected to the wire 43 which supplies the distributor with 40 high tension current. The plate 42 is connected to the wire 44 which leads to the high tension coil 45 of the motor. The coil 45 is connected to the battery through the usual ignition switch 46. The plates 41 and 42 are suspended in the body 15 by a pair of insulating sleeves 47 and 48. The sleeves 47 and 48 extend through nipples 49 and 50 of the cap 16. Contact is established between the plates 41 and 42 by means of a conducting plate 51 which is apertured to slide freely over the insulating sleeves 47 and 48 and normally rest by gravity on the upper surfaces of the plates 41 and 42. Normally therefore the circuit between the coil 45 and the distributor is closed. The body 60 of the reservoir 15 contains a float 52 which is of conical shape on its lower side to fit closely with the bottom of the reservoir. The upper side of the float 52 is provided with a stem 53 which is so positioned as to pass between the plates 41 and 42 when the float is in uppermost position. It will be seen how the stem 53 lifts the plate 51 65 from the contacts 41 and 42. Figure 4 of the drawings illustrates the extreme upper position of the float and shows conducting plate 51 in circuit breaking position. Preferably the stem 53 of the float is of non-conducting material so that any lateral displacement thereof will not close the circuit between the plates 41 and 42.

There are several ways of operating the device 70 with the automatic ignition switch. For in-

stance, after the car has been running and it is desired to park the same as by putting it in the garage for the night the valve 34 can be closed, the valves 26 and 29 opened and the car left. The suction of the engine will raise oil from the 5 crankcase into the reservoir until a sufficient quantity is present to buoy the float 52 to the top of the reservoir. When the float 52 nears the top of the reservoir its stem 53 will lift the plate 51 and cut the ignition circuit thereby stopping the 10 motor. The oil which was warm by reason of the running of the car will hold its heat to a substantial degree overnight and to start the car it is only necessary to open the return valve 34 15 which lets the float 52 descend in the reservoir and permits the closing of the ignition circuit.

Of course the operator can remain in the car 20 until the ignition circuit is broken by the float 52 and then turn off the ignition switch on the control panel.

Referring now to Figures 6 and 7, a construction is illustrated which embodies a switch which prevents arcing and eliminates any danger of fire which may exist when the reservoir is filled 25 with hot oil. In this construction a guide rod 54 passes through the cap 16' and is held by the nut 55 which is threaded over the corresponding threaded upper end of the rod. The lower end of the rod 54 is provided with a head 56 which 30 acts as a stop for the float 57 through the central portion of which the rod 54 is loosely passed. The float 57 will be free to move vertically on the rod 54 as the oil level in the reservoir rises or falls. The upper part of the rod 54 is provided 35 with a pin 58 upon which a bracket 59 is pivotally mounted. The bracket 59 serves to hold an enclosed mercury switch 60 in an end of which a pair of spaced contacts 61 are located. The bracket 59 has an extension 62 which is pivoted 40 to the link 63 pivotally carried upon a stud 64 of the float 57. The mercury switch 60 is adapted to be closed when the float 57 is in its lower positions. As the oil level rises the float 57 lifts the link 63 which tilts the bracket 59 and switch 60 45 about the pivot 58. The mercury in the switch eventually uncovers the two contacts 61 and opens the circuit. The contacts 61 are connected electrically to binding posts 65, 66 secured to the cap 16', such connection being through the lead 50 wires 67, 68. One of the binding posts 65, 66 is adapted for attachment to the distributor supply wire and the other post is adapted for attachment to the coil which supplies the motor with 55 sparking current.

The modified device shown in Figures 6 and 7 also employs an air vent to admit air into the reservoir to replace the oil as it drains back into the crankcase. This vent consists in a short length of pipe 69 which passes through the cap 60 16' and opens into the reservoir. The pipe is provided with a valve 70 which is shown as a simple turning plug valve. A control rod 71 connects to the plug of the valve 70 and extends through to the driver's side of the instrument panel where 65 it carries a knob 72 for manual operation. The knob 72 has an indicator finger 73 attached thereto and the instrument panel 39' carries an index plate 74 on which suitable markings indicate the opened and closed positions of the air 70 vent 70 and the oil return valve to be described. In this form of device the oil return valve is of the turning plug type and is located at 75 in the return pipe 18. A yoke 76 connects a control rod 77 with the stem of the turning plug. The 78

two control rods 11 and 17 converge and the adjacent ends are journalled in a bracket 18 secured to the front side of the instrument panel. Each of the rods 11 and 17 has a bevelled gear 19 attached thereto and located in intermeshing relation. It will therefore be seen that the valves 10 and 15 are opened and closed in unison by the turning of the knob 12 by the driver. The provision of the air inlet permits much more rapid drainage of oil than is possible without it although due to the large diameter of the oil return pipe a volume of air is gradually allowed to find its way into the reservoir to replace the oil as it drains out in the form shown in Figs. 1 to 5. 10 The device is of simple construction and requires only two simple controls, one which controls the vacuum and the oil intake, and the other which controls the oil return. The reservoir can be made for any desired capacity, and will depend largely upon the crankcase capacity of the car to which it is applied. A thermos container is preferred for the oil reservoir but it is obvious that any heat insulated container would be operative to a greater or lesser degree. In very cold climates it is desirable to use the most highly insulating container possible. 15

In addition to providing proper lubrication for a motor when starting it in cold condition the provision of a supply of warm oil softens the oil remaining in the crankcase and makes it easy for the starter to turn over the engine. This reduces the strain on the battery in cold weather. The warm oil also assists in warming the whole engine so that the efficient operating temperature is more quickly obtained. 30

It is obvious that various changes and modifications may be made in the details of construction and design of the above specifically described embodiment of this invention without departing from the spirit thereof, such changes and modifications being restricted only by the scope of the following claims:

What is claimed is:

1. A device for retaining heat in motor oil comprising a heat insulated reservoir, an oil connection between the crankcase and said reservoir, means for transferring oil from the crankcase to the reservoir, and means for maintaining the ignition circuit of the motor open when a predetermined quantity of oil is present in said reservoir. 45

2. A device for retaining heat in motor oil comprising a heat insulated reservoir, an oil connection between the crankcase of the motor and said reservoir, means for transferring oil from the crankcase to the reservoir, a float in the reservoir adapted to be raised by oil therein, and means operable by said float for opening the ignition circuit of the motor upon the presence of a predetermined quantity of oil in said reservoir, whereby the motor cannot be run while the predetermined quantity of oil is in the reservoir. 55

3. A device for retaining heat in motor oil comprising a heat insulated reservoir, an oil connection between the crankcase and the reservoir, means for transferring oil from the crankcase to the reservoir, a pair of spaced electrical contacts breaking the ignition circuit of the motor, a bridging contact biased to close the ignition circuit, said spaced contacts and bridging contact being located in the upper part of said reservoir, and a float in said reservoir adapted to be raised by oil therein to move said bridging contact to

open the ignition circuit upon the presence of a predetermined quantity of oil in the reservoir. 5

4. A device for retaining heat in motor oil comprising a heat insulated reservoir, an oil connection between the crankcase of the motor and the reservoir, means for transferring oil from the crankcase to the reservoir, a pair of spaced electrical contacts breaking the ignition circuit of the motor and located in the upper part of the reservoir, a bridging contact plate resting upon 10 said spaced contacts and biased by gravity to maintain the ignition circuit closed, and a float in the reservoir adapted to be raised by oil therein, said float having a stem at its upper side positioned to engage said bridging plate when the float is raised to a predetermined position whereby to lift said bridging plate from said spaced contacts and open the ignition circuit of the motor. 15

5. A device for retaining the heat in motor oil 20 of an automobile comprising a reservoir with side walls of Dewar construction, a cap on said reservoir, an oil connecting pipe opening into a lower part of the crankcase of the motor and opening through said cap, a valve in said pipe, a 25 vacuum pipe connecting the fuel intake of the motor with the reservoir and opening through said cap, a valve in said connecting pipe, an oil return pipe connecting the bottom of the reservoir with the upper part of the crankcase, a 30 valve in said return pipe, a manually operable control extending through the instrument panel of the automobile for simultaneously controlling the valves in the connecting oil pipe and the vacuum pipe whereby the operator of the car can 35 open or close both valves, and a manually operable control for the return pipe valve extending through the instrument panel of the car so that the operator may control said valve. 40

6. A device for retaining heat in motor oil 45 comprising a heat insulated reservoir, an oil connection between the crankcase and the reservoir, means for transferring oil from the crankcase to the reservoir, an enclosed mercury switch normally completing the ignition circuit of the 45 motor, a float in said reservoir adapted to be raised by oil therein, and means connecting said float and switch whereby to open said switch when the oil reaches a predetermined level in said reservoir 50 to open the ignition circuit and prevent operation of the motor.

7. In combination with an internal combustion engine having a crankcase holding a normally heated and fluent body of lubricant, a device for retaining the fluidity and high temperature of the lubricant comprising a reservoir separate and remote from the crankcase, heat insulation extending all about said reservoir, an inlet conduit between said crankcase and an upper part of said reservoir, a valve in said inlet conduit, an outlet conduit from a lower part of said reservoir to the crankcase, a valve in said conduit, means for opening and closing said last named valve, a vacuum connection between the engine intake and the upper part of said reservoir, a valve in 60 said vacuum intake, and means for conjointly opening and closing the first and last named valves whereby to produce a condition of vacuum in said reservoir while the lubricant is being drawn up through said inlet conduit and for simultaneously shutting off the communication of the reservoir with the engine intake and said crankcase. 65
